UNITED STATES PATENT OFFICE.

FRANK A. MARCHER, OF LOS ANGELES, CALIFORNIA.

EYEGLASS-FRAME.

No 926,667.

Specification of Letters Patent. Patented June 29, 1909.

Application filed September 13, 1907. Serial No. 392,808.

To all whom it may concern:

Be it known that I, FRANK A. MARCHER, a citizen of the United States, residing at Los Angeles, in the county of Los Angeles and State of California, have invented a new and useful Eyeglass-Frame, of which the following is a specification.

An object of this invention is to provide a means for rigidly uniting the bow-spring and nose-guards to the studs of eye glasses without the use of screws, where the spring and guards are made of wire, thereby rendering the manufacture of the same cheaper than other forms are capable of being produced, and also permitting by thus employing wire, of an accurate adjustment to the bridge of any nose, on account of the fact that the same can be bent into all shapes by the use of an ordinary pair of pliers.

The accompanying drawings illustrate the invention.

Figure 1 is a fragmentary front elevation. Fig. 2 is a transverse section on line x^2-x^2 , Fig. 1. Fig. 3 is a mid-section on line x^3-x^3 , Fig. 2. Fig. 4 is a fragmentary mid-section on line x^4-x^4 , Fig. 3, the pin being shown in dotted lines. Fig. 5 is a detail of the pin detached. Fig. 6 is a fragmentary, sectional detail showing the position of the pin for permitting separation of bow-spring ends and nose-guards. Fig. 7 is a fragmentary, perspective detail of the nose-guard and bow-spring ends showing offset portions, shoulders, and notches.

1 designates a lens; 2, a studding therefor provided with a tubular body 3 which is made preferably integral with the stud 2.

4 is an orifice provided in the stud 2, the said orifice communicating or registering with an opening 5 provided in the tubular body 3.

6 designates the extremity of the arm of a bow-spring 7, the said extremity being provided with a shoulder 8 and reduced flat portion 9.

10 is a notch or recess provided in one side of the reduced portion 9 of the extremity of the bow-spring-arm.

11 designates the extremity of the nose-guard, the said extremity being provided with a shoulder 12 and with a reduced flat portion 13, as well as with a recess or notch 14. This reduced portion is adapted to slide over the reduced or flat portion 9 of the extremity of the bow-spring-arm and abut against the shoulder 8, whereby the recess 10

of the bow-spring and the recess 14 of the nose-guard are brought into register.

The respective extremities of the bow-spring and the nose-guards are adapted to be housed in the sleeve or tubular body 3, and in order to prevent their disengagement or disassociation, the pin 15 engages the orifice 4 provided in the stud and extending in the path of the slot or opening 5 provided in the tubular body. This pin is upset on one side of the stud, as seen at 16, and is provided with a screw-head 17 on the other end which is adapted to be seated in a countersunk portion 18 provided in the stud.

The pin is provided approximately midway of its length with a notch or groove 19. The manipulation of the pin through the medium of the screw-head and the registration of the notched portion 19 thereof with the respective recesses or notches 10 and 14 of the bow-spring and nose-guard extremities respectively, permits of a separation of the two for purposes of adjustment, repair, or justification of the parts.

When the cylindrical portion of the pin is in engagement with the notched portions of the bow-spring and nose-guard extremities, the union of the same is assured, and the separation of the two impossible until the pin is manipulated so as to bring the notched portion thereof into engagement and in register with the like notched portion of the extremities of the bow-spring and the nose-guards.

In order to facilitate the locking and unlocking of the parts a suitable mark may be placed upon the screw-head, and another one upon the stud by the side of the screw-head, so that when the screw is turned in line with the notch on the stud the position of the screw will be such that the parts are unlocked and capable of separation. When, however, the mark on the screw is in a position opposite the mark on the screw-head, the pin is in positive engagement with the notches of the parts which are thereby positively locked. It will be noted that there are no unsightly projections caused by the provision of this pin because the same is countersunk on both sides.

What I claim is:

1. An apertured lens stud, a sleeve thereon provided with an opening communicating with the aperture of said stud, a bow-spring and a nose-guard, the respective extremities of which are rabbeted and adapted to mutu-

ally engage and also to fit the bore of the sleeve, said rabbeted portions also being provided with notches, and a rotatable member extending through the aperture in said stud 5 for engaging said notches in the extremities of said bow-spring and nose-guard to lock or unlock the same from each other and the sleeve.

2. The combination with a stud provided 10 with an orifice and a sleeve provided with an opening communicating with the orifice of said stud, said stud being adapted to receive the respective rabbeted extremities of a nose-guard and bow-spring which mutually engage 15 within the bore of the sleeve, of a pin extending through said orifice provided with a notch, said pin being adapted to lock or unlock said nose-guard and bow-spring extremities from their locking positions.

20 3. A frame comprising a pair of lens studs, each provided with a tubular sleeve, a rabbeted nose-guard housed in each of said sleeves, a one-piece bow-spring having rabbeted ends also housed in said sleeves and arranged to engage with said nose-guards, and means for locking the engaging nose-guards and bow-spring ends in said sleeves.

4. A frame comprising a pair of lens studs, each provided with a tubular sleeve, a rabbeted nose-guard housed in each of said sleeves, a one-piece bow-spring having rabbeted ends also housed in said sleeves and arranged to engage with said nose-guards, said nose-guards and bow-spring ends being 35 provided with coinciding notches, and a pin provided with a notch and in operative re-

lation to said notches of the nose-guard and bow-spring whereby the registration of the respective notches will unlock the interlocking nose-guards and bow-spring ends, and 40 lock the same when the notch of the pin is out of register.

5. An eye-glass frame comprising a pair of lens-studs each provided with a sleeve, there being transverse openings at the junction of 45 the sleeves with the studs, said openings cutting into the sleeves, rabbeted nose-guards housed one in each of said sleeves and having notches registering with said transverse openings; a bow-spring having rabbeted ends 50 matching the rabbets of the nose-guards and having notches registering with the notches of the nose-guards and housed in said sleeves, and pins in said transverse openings and engaging in said notches, said pins having 55 releasing notches.

6. A frame comprising a pair of lens-studs, each provided with a sleeve, rabbeted notched nose-guards housed one in each of 60 said sleeves, a one-piece notched bow-spring having rabbeted ends, also housed in said sleeves and arranged to engage with said nose-guards, and notched pins for locking the 65 engaging nose-guards and bow-spring ends in said sleeve.

In testimony whereof, I have hereunto set my hand at Los Angeles California this 7th day of September 1907.

FRANK A. MARCHER.
